ABRASIVE STRIP HOLDER

Alvin O. Olafson, St. Paul, Minn.

Application March 26, 1947, Serial No. 737,243

12 Claims. (Cl. 51—187)

1

My invention relates to an improvement in abrasive strip holders wherein it is desired to provide a simple and efficient device for holding a strip of flexible material such as emery cloth or the like.

It is the object of the present invention to provide a means of supporting an elongated strip of abrasive material or the like so that it may be used much in the manner of a file. The strip of abrasive material is stretched taut over an elongated flat surface. Means is provided for clamping the abrasive strip in this position so that it may be easily used.

A feature of the present invention lies in the provision of a holder for a strip of flexible material which comprises an elongated flat support against which the flexible strip is held and a handle at one end of this support. The handle provides a means by which the abrasive strip may be easily manipulated.

A feature of the present invention lies in the provision of an elongated support having a handle at one end thereof and in so designing the handle that it may be used to clamp a strip of abrasive material or the like to the support. The handle comprises a pair of clamping plates movably supported on the elongated support. In one position of these plates, portions of the plates are spread apart to receive the ends of the abrasive strip. In a second position the plates clamp against the strip to hold the same firmly supported.

A feature of the present invention lies in the provision of a holder for a strip of abrasive material or the like which comprises an elongated pair of substantially parallel clamping strips between which one end of the abrasive strip may be anchored if desired. Movable handle means is provided for clamping these clamping strips together to hold the abrasive strip in any desired position.

A feature of the present invention lies in the provision of a means of supporting a strip of abrasive material or the like in adjusted position. By merely moving the handle of the support the strip may be clamped in place or released from clamped position. As a result it is possible to progressively use the strip of abrasive material by moving the abrasive strip longitudinally when a portion thereof becomes worn.

2

These and other objects and novel features of my invention will be more clearly and fully set forth in the following specification and claims.

In the drawings forming a part of my specification:

5 Figure 1 is a perspective view of my abrasive strip holder showing the construction thereof.

Figure 2 is a side elevational view of the holder in position to receive an abrasive strip.

Figure 3 is a view similar to Figure 2 showing the abrasive strip clamped in place.

Figure 4 is a view similar to Figure 3 showing an abrasive strip clamped in a somewhat different manner.

15 Figure 5 is a longitudinal sectional view through the abrasive strip holder.

Figure 6 is a perspective view of the spring hinge connecting the parts of the handle.

Figure 7 is a sectional view through the handle, the position of the section being indicated by the line 7—7 of Figure 3.

20 The abrasive strip holder is of simple construction and in preferred form includes only four separate parts, two of which are identical. As a result the holder is inexpensive to manufacture and to assemble.

An elongated strip 10 of metal or other suitable material is centrally bent at 11 to form a pair of clamping strips 12 and 13. The free ends

30 14 and 15 of the strip 10 are in contiguous relation when pressed together. The central bend 11 forms a closed connecting end resiliently connecting the clamping strips 12 and 13 so that they may spread slightly apart as illustrated in

35 Figure 2 of the drawings, or may be pressed together as illustrated in Figures 3, 4, and 5.

The forward ends of the strips 12 and 13 extend in parallel relationship to a point spaced from the closed end 11 at which point the strips

40 diverge apart or are off-set as indicated at 16 and 17. From the point of off-set the strips 12 and 13 are provided with straight portions 19 and

45 20 which incline slightly toward each other, terminating in off-sets 21 and 22, respectively, which bring the strips into contacting relation. Short parallel contacting portions 23 and 24 are connected to the off-set 21 and 22 and rearwardly of these contacting portions the strips diverge apart as indicated by the numerals 25 and 26. Slight-

50 ly diverging spaced strip portions 27 and 29 con-

nect the diverging portions 25 and 26 to the closed end 11. The diverging portions 25, 26, 27 and 29 act as cams or wedges as will be later described in detail.

The handle of my holder is formed of two identical clamping plates 30 and 31 which are connected by a spring 32. The spring 32 acts as a spring hinge to permit the plates to pivot relative to each other and to spread apart the forward ends of the clamping plates in one position thereof.

The clamping plate 30 is generally channel-shaped in cross section and includes a top plate 33 having parallel side flanges 34 depending downwardly from opposite side edges thereof. At the forward end of the plate 34 an off-set 35 is provided which supports a clamping flange 36. As illustrated in Figure 7 of the drawings a pair of opposed flanges 37 extend inwardly from the side flanges 34 in opposed relation at a point near the longitudinal center of the top plate 33.

The handle member 31 is identical in shape to the handle member 30 and is supported in opposed relation thereto. The handle member 30 includes a bottom plate 39 having upwardly extending side flanges 40 on opposite longitudinal edges thereof. An off-set 41 is provided at the forward end of the bottom plate 39 which supports the clamping flange 42. The clamping flange 42 is in opposed relation to the similar flange 36 of the handle member 30. As illustrated in Figure 7 of the drawings a pair of opposed inwardly projecting flanges 43 are provided on the upper edge of the side flanges 40 near the longitudinal center of the handle member 31. The spring 32 is constructed as best illustrated in Figure 6 of the drawings. The spring includes a pair of arms 44 and 45 connected along a fold line 46 so that the arms 44 and 45 normally tend to diverge apart as illustrated in this figure. A pair of spaced ears 47 are provided along the free edge of the arm 44, these arms being bent to underlie a portion of the arm 44. A similar pair of ears 49 is provided on the free edge of the spring arm 45. The ears 49 are bent to underlie a portion of the spring arm 45 in spaced relation thereto. The arms 47 and 49 are designed to hook over the ends of the flanges 37 and 43 of the handle members 30 and 31.

As best seen in Figure 5 of the drawings the spring arm 45 overlies the flanges 37 of the handle member 30 with the folded edge 46 of the spring extending downwardly along the rear edge of these flanges. The hook shaped ears 49 are bent to fold about the forward edges of the flanges 37 so as to hold the spring arm 45 locked to the flange 37. Similarly the spring arm 44 lies beneath the flanges 43 of the handle section 31. The connecting fold 46 lies rearwardly of these flanges 43 and the hook shaped ears 47 hook upwardly about the forward edges of these flanges. Thus the spring 32 tends to urge the clamping flanges 36 and 42 apart and the spring serves as a hinge between the handle sections 30 and 31.

It will be noted that when the spring hinge 32 is in place connecting the handle members 30 and 31, it extends between the spaced portions 19 and 20 of the clamping strips 12 and 13. The movement of the handle sections longitudinally relative to the clamping strips is limited by the length of the spaced portions 19. When the handle sections are moved forwardly a sufficient distance the forward edges of the spring hinge

32 engages against the off-sets 16 and 17 in the clamping strips. Movement of the handle sections in a rearward direction is also limited by the off-sets 21 and 22. However, the rear edges of the handle sections engage against the outwardly diverging portions 25 and 26 and the slightly diverging portions 27 and 29 to clamp the clamping flanges 36 and 42 against the strips 12 and 13 before the handle reaches its rear extreme position.

The operation of my holder is believed obvious from the foregoing description. A strip of sand paper, emery cloth, sand cloth, or any strip of flexible material B may be centrally doubled as illustrated in Figure 4 of the drawings so that the strip engages over the outer exposed surface of both the clamping strips 12 and 13. The ends of the flexible strip are inserted beneath the clamping flanges 36 and 42 while the handle is in the open position shown in Figure 2 of the drawings. The handle sections are next grasped and moved longitudinally of the clamping strips. As a result the rear edges of the handle sections 30 and 31 are wedged apart by the diverging portions of the strips 12 and 13 near the closed connecting end 11, forcing the forward ends of the handle sections and the clamping flanges 35 toward the clamping strips 12 and 13. As a result the ends of the flexible strip are clamped between the clamping flanges 36 and 42 and the respective clamping strips 12 and 13.

In moving the handle sections longitudinally of the clamping strips it is usual practice to hold the handle sections in the hand and to strike one end of the clamping strips against a solid object. If the handle is to be moved from the position illustrated in Figure 2 into clamping position the handle sections are held in the hand and the closed end 11 is struck against a solid object. In releasing the handle from clamped position, it is only necessary to strike the free ends 14 and 15 of the clamping strip on a solid object while holding the handle sections.

In Figure 3 of the drawings a modified manner of holding the clamping strip is illustrated. In this arrangement an abrasive strip B is placed to overlie the exposed surface of one of the clamping strips 12 or 13 with one end of the abrasive strip inserted between the strips 12 and 13. The other end of the flexible strip B is inserted between the corresponding clamping flange 36 or 42 and the clamping strip. The handle sections are moved in the manner previously described, and the strip B is firmly held in place as the clamping flanges act not only to clamp the flexible strip against the clamping strip, but also to clamp the two clamping strips together. As the strip is used and becomes worn, the handle can be moved to relieve the clamping pressure, the strip may be moved longitudinally, and the handle again moved to clamping position.

As a result the strip may be progressively used. This is particularly important when only one small section of the exposed surface of the abrasive material is being used. If desired the ends of two strips may be inserted between the clamping strips 12 and 13 as illustrated in Figure 3, one strip B extending over the surface of the clamping strip 12 and the other strip extending over the exposed surface of the clamping strip 13. Both strips may be anchored in place in the manner described and adjusted in position whenever desired.

It will be seen that my holder is capable of holding any strip of flexible material and acts

to stretch the material tautly over the surface of the holder when engaged. My holder is particularly useful in holding abrasive material such as emery cloth and the like which is often supplied in strip form. Abrasive in strip form may be purchased in rolls and any desired length may be employed. Obviously a sheet of sand paper or cloth may be cut into strips if desired.

It will be noted that in moving the handle sections from the position shown in Figure 2 to the clamping position shown in the other figures, the handle sections are moved toward the rear end of the handle. As a result the clamping flanges tend to pull the flexible strip tautly over the surface of the clamping strips 12 and 13 as the handle is moved to clamping position.

In accordance with the patent statutes, I have described the principles of construction and operation of my abrasive strip holder, and while I have endeavored to set forth the best embodiment thereof, I desire to have it understood that obvious changes may be made within the scope of the following claims without departing from the spirit of my invention.

I claim:

1. A holder for flexible strip material comprising an elongated support, a pair of opposed clamping members slidably supported on said support, said clamping members being hingedly supported for movement into or out of clamping position on opposite sides of said support, and wedge means on said elongated support engageable with said clamping members upon longitudinal movement thereof for hinging said clamping members into clamping position.

2. A holder for flexible strip material comprising an elongated support over which the flexible strip may extend, a clamping member longitudinally slidable on said support and hingedly connected thereto, said clamping member being hingeable into or out of clamping position, and means on said longitudinal support engageable with said clamping member upon longitudinal movement thereof for urging said clamping member into clamping position.

3. A holder for flexible strip material comprising an elongated support, a clamping plate slidably and hingedly connected at a point intermediate its ends to said support, and means on said elongated support for hinging said clamping means upon longitudinal movement thereof relative to said support.

4. A holder for flexible strip material comprising an elongated support, a clamping member longitudinally slidable on said support, said clamping member being slidably and hingedly connected to said support along a transverse hinge line intermediate the ends of the clamping member, and means on said support engageable with one end of said clamping member upon longitudinal slidable movement thereof to urge the other end into clamping relation with said support.

5. A holder for flexible strip material comprising an elongated support over which the strip material may extend, a pair of clamping members hingedly connected along a transverse hinge line intermediate the ends of said clamping members, means slidably supporting said clamping members to said support, and means on said support engageable with one end of each of said clamping members to pivot the other ends thereof against said support.

6. A holder for flexible strip material compris-

ing an elongated support, a pair of clamping members on opposite sides of said support, means hingedly connecting said clamping members along a transverse hinge line intermediate the ends thereof, an aperture through said elongated support through which said hinge means extends, and means on said support engageable with one end of each of said clamping members to separate these ends to hinge the other ends thereof against said support.

7. A holder for elongated strip material comprising a pair of clamping strips connected at one end and arranged in substantially parallel relation, a pair of clamping members slidably supported on said clamping strips, one of said clamping members overlying a corresponding clamping strip, means hingedly connecting said clamping members at a point intermediate the ends thereof, and means for urging one end of said clamping members apart upon longitudinal movement thereof relative to said clamping strips to urge the other ends of the clamping members against said clamping strips.

8. A holder for flexible strip material comprising a pair of clamping strips arranged in parallel relation and connected at one end, the pair of clamping members arranged on opposite sides of said clamping strips, means hingedly connecting said clamping members, said clamping members being movable longitudinally of said clamping strips, and means for pivoting said clamping members upon longitudinal movement thereof relative to said clamping strips.

9. A holder for flexible strip material including a pair of clamping strips arranged in substantially parallel relationship and connected at one end, said strips being off-set near said one end to space the strips apart at this point, a pair of clamping plates arranged on opposite sides of said clamping strips, and means hingedly connecting said clamping plates, said hinge means extending between said clamping strips at the point where they are spaced apart.

10. A holder for flexible strip material comprising a pair of clamping strips arranged in parallel relation and connected at one end, a pair of clamping plates hingedly and slidably connected to said clamping strips, and means on said clamping strips for pivoting said clamping means upon longitudinal movement thereof relative to said clamping strips.

11. A holder for flexible strip material including a pair of clamping strips arranged in substantially parallel relation and connected at one end, said strips being off-set near said one end to provide a space between said strips at this point, a pair of clamping plates on opposite sides of said clamping strips, a coupling member between said clamping strips at the point where they are spaced apart, said coupling member being connected to both of said clamping plates at a point intermediate the ends thereof, and means on said clamping strips for urging one end of said clamping plates apart upon longitudinal movement of said clamping plates relative to said clamping strips.

12. A holder for flexible strip material comprising a pair of clamping strips connected together at one end, said clamping strips extending in substantially parallel relation, an off-set portion in said clamping strips near said one end to form a space between said clamping strips at this point, clamping plates on opposite sides of said clamping strips, flanges on said clamping plates extending on opposite sides of said clamp-

ing strips, inwardly extending opposed ears on said flanges, said ears extending into said space between said strips, a spring coupling member connecting the ears of one clamping plate to the ears of the other, said clamping strips being formed to engage against one end of said clamping plates upon longitudinal movement of said plates in one direction to pivot the opposite ends of the clamping plates against said clamping strips.
